PERCY C. DAY, OF MILWAUKEE, WISCONSIN, ASSIGNOR TO THE FALK CORPORATION, OF MILWAUKEE, WISCONSIN, A CORPORATION OF WISCONSIN.

ELEVATOR DRIVE.

Application filed December 8, 1921. Serial No. 520,843.

This invention relates to power units, for use primarily in driving elevators, such as grain elevators and the like, although certain novel features thereof may be advantageously employed in other relations.

In elevators of the type mentioned, the elevator buckets are ordinarily carried by a substantially vertically disposed endless belt trained over and driven by a pulley of standard construction. These belts are not infrequently two hundred feet or more in length. To insure proper tracking, precise adjustments of the pulley and pulley shaft are necessary, not only at the time of installation but also from time to time thereafter, in order to compensate for the uneven stretching of the belt under continued use.

One object of the present invention is the provision of a geared unit well adapted for driving an elevator pulley and constructed to permit an angular adjustment of the pulley shaft.

Another object is the provision in an elevator drive mechanism of an improved means for preventing reverse rotation of the elevator pulley.

Another object is generally to improve the construction and operation of devices of this character.

Other more specific objects and advantages will hereinafter appear.

One embodiment of this invention is illustrated in the accompanying drawings, in which:

Figure 1 is a view in side elevation of an elevator drive mechanism embodying features of the present invention.

Figure 2 is a sectional view taken substantially on the line 2—2 of Figure 1.

Figure 3 is a vertical sectional view, on a somewhat larger scale, of the drive mechanism shown in Figure 1.

Figure 4 is a sectional view of a detail taken substantially on the line 4—4 of Figure 3.

Figure 5 is a detail on a somewhat larger scale of a back stop mechanism shown in Figure 3.

Figure 6 is a sectional view taken substantially on the line 6—6 of Figure 5.

The elevator drive mechanism selected for illustration includes a main shaft 10 having a pulley 11 of standard construction keyed or otherwise fixed thereto. The pulley constitutes a support and driving means for an

endless belt 12 trained thereover and constituting the usual conveying medium for the elevator buckets (not shown).

The shaft 10 is journaled at one end in a bearing 13, fixed in an angularly adjustable bearing block 14, supported upon a vertically adjustable standard 15, preferably such as will now be described. The standard shown includes a rigid frame comprising a base plate 16, having uprights 17 mounted thereon and supporting the main body portion 18. A plunger 19 is mounted for vertical adjustment in a suitable guideway 20 formed in the body portion. The plunger carries a bed plate 21 having a concave seat 22 of cylindrical contour for receiving the correspondingly shaped convex face 23 of the bearing block 14. The curvature of the face 23 and seat 22 is such as to permit an angular adjustment of the bearing block 24 about a horizontal axis at right angles with the axis of the shaft 10. The bearing block is retained in its seat by any appropriate means, such as the cooperating flanges 24 and 25, on the block and bed plate; and the bed plate is retained against turning by any appropriate means, such as the upstanding guide flanges 26 carried by the frame. Vertical adjustment of the plunger 19 is secured preferably by the use of a jack-screw 27, herein shown as swiveled, as at 28, in the base plate 16 and threaded through a nut 29 secured to the plunger.

The other end of shaft 10 is journaled in bearings 30, fixed in a rigid frame 31, pivotally mounted for angular adjustment about a substantially horizontal axis at substantially right angles with the shaft 10. A support of any appropriate construction may be provided for the frame. That shown includes a base 32 having A-frames 33, preferably of hollow construction, rigidly mounted at the opposite ends thereof and constituting upright standards for sustaining the weight of the frame and parts carried thereby. These standards are provided with axially aligned bearings 34 for journally receiving trunnions 35 fixed in suitable sockets 36 in protuberances 37 projecting from the sides of the frame. By this mounting, the frame 31 is permitted to adjust itself to any changes in the angularity of the shaft 11 resulting from a vertical adjustment of the standard 15.

The frame 31 carries the gears for driving

the shaft 10 and in the form shown includes a gear casing 38 having an upper removable section 39 and a lower section 40 of which the protuberances 37 form an integral part. 5 A shaft 42 is journaled in bearings 43 provided in the upper section 39 of the casing, this section being separable along the axial plane of the bearings 43 for purposes of assembly. Shaft 42 carries a drive pinion 44, 10 preferably of the herring-bone type, meshing with a corresponding gear 45 keyed or otherwise fixed to the shaft 10.

An electric motor 46 of any standard or approved type is preferably employed for 15 driving the shaft 42. In the mechanism shown, this motor is carried by a rigid bracket 47, preferably of hollow construction, secured to or formed as an integral part of the main frame 31. This motor may be mechanically connected with the shaft 42 through a clutch, although a flexible coupling 48, of a well known construction, is employed for this purpose in the mechanism shown. 20

25 In the construction hereinabove described, it will be noted that the shaft 10, together with the entire driving mechanism therefor, may be readily adjusted as a unit whenever it is desired to effect an angular adjustment 30 of the pulley 11.

Provision is also preferably made to prevent reverse rotation of the shaft 10 which might otherwise occur under the influence of the loaded elevator buckets, due to a failure in the power circuit or from any other cause. In the mechanism shown, this is accomplished by the use of a ratchet mechanism, such as will now be described. This mechanism includes a spider 49 keyed or 35 otherwise fixed to one end of the shaft 42 and carrying a plurality of pawls 50 engageable with a fixed ratchet 51 secured to the main frame 31. As shown, particularly in Figures 5 and 6, these pawls are three in 40 number and each is pivotally mounted upon a pintle 52 secured within the outer end of the spider leg 53. Each pawl is biased toward ratchet engaging position by a light spring 54 connected between a lug 55 carried by the pawl and a lug 55' carried by the spider. Each pawl is preferably so proportioned or weighted as to be swung against the tension of the spring 54 by centrifugal force out of engagement with the ratchet 45 during normal rotation of the shaft 42. Unnecessary wear and clatter between the pawls and ratchet teeth during normal operation is thus avoided. As soon as rotation of the shaft 42 has stopped, however, the pawls are 50 forced by the spring 54 into ratchet engaging position to prevent rotation of the shaft in an opposite direction. To insure proper action of the pawls, suitable anti-friction 55 bearings 56 between the pawls and spindles are preferably employed. In the mechanism

shown, the number of teeth on the ratchet is preferably other than an exact multiple of the number of pawls, so that a differential engagement between the several pawls and ratchet is secured. This mechanism is preferably enclosed in an appropriate casing 57 which may be conveniently secured to the main frame 31. 70

Various changes may be made in the embodiment of the invention hereinabove specifically described, without departing from or sacrificing any of the advantages of the invention as defined in the following claims. 75

I claim:

1. In an elevator head the combination of 80 a shaft, a belt supporting pulley carried by said shaft intermediate the ends thereof, a vertically adjustable support for one end of said shaft, a gear casing supporting the other end of said shaft, gears in said casing for driving said shaft, and a pivotal support for said casing permitting said pulley, shaft and gears to be adjusted as a unit to effect proper tracking of said pulley. 85

2. In an elevator head the combination of 90 a shaft, a belt supporting pulley carried by said shaft intermediate the ends thereof, a vertically adjustable support for one end of said shaft, a frame supporting the other end of said shaft, a motor carried by said frame, speed reduction gears carried by said frame between said motor and shaft, a pivotal support for said frame permitting said pulley, shaft and gears to move as a unit in response 95 to adjustment of said support. 100

3. The combination of a frame, a shaft journaled therein and projecting therebeyond, mechanism carried by said frame for driving said shaft, a pivotal support for said frame, a rockable bearing block for supporting the projected portion of said shaft, and a vertically adjustable support for supporting said block. 105

4. An elevator drive mechanism having a 110 main frame, a support for said frame, a drive shaft journaled therein, a pulley shaft journaled in said frame, gear connections between said drive shaft and said pulley shaft, means associated with said drive shaft and frame for preventing rotation of said pulley shaft except in one direction, and means for adjusting said frame with respect to said support without impairing the functioning 115 of said last named means. 120

5. An elevator drive mechanism having a 125 main frame, a drive shaft journaled therein, a pulley shaft journaled in said frame, gear connections between said shafts, means including a pivotal support for said frame permitting an angular adjustment of said frame and shafts, and means associated with said drive shaft for preventing rotation thereof except in one direction in all angular positions of said frame. 130

6. An elevator drive mechanism having a

frame, a shaft journaled therein, a pulley shaft journaled therein, speed reduction gears between said shafts, a fixed ratchet wheel carried by said frame, a pawl carried by said first named shaft and cooperating with said ratchet wheel to prevent rotation of said first named shaft except in one direction, said pawl being constructed to swing clear of said ratchet wheel during normal rotation of said first named shaft, and means for yieldably forcing said pawl into engagement with said ratchet wheel when said first named shaft is at rest. 7. An elevator drive mechanism having a frame, a drive shaft journaled therein, a pulley shaft journaled therein, speed reduction gearing between said shafts, and cen-

trifugal means associated with said drive shaft for preventing rotation thereof except in one direction, said means including a fixed 20 ratchet wheel secured to said frame, a plurality of pawls carried by said drive shaft for cooperation with said ratchet wheel, said ratchet wheel having a number of ratchet teeth not a multiple of the number of pawls, 25 said pawls being constructed to swing clear of said ratchet teeth during normal rotation of said drive shaft, and means for yieldably forcing said pawls into engagement with said teeth when said drive shaft is brought 30 to rest.

In witness whereof, I hereunto subscribe my name this 26th day of November, 1921.

PERCY C. DAY.
